CLAIM

The ornamental design for a display screen portion with
graphical user interface for augmented reality, as shown and
described.

DESCRIPTION

FIG. 1 is a front view of a display screen portion with a
graphical user interface with a left panel and a center panel
for augmented reality showing the new design in a first
embodiment; and,

FIG. 2 is another front view of a display screen portion with
a graphical user interface with a left panel and a center panel
for augmented reality showing the new design in a second
embodiment.

In FIGS. 1-2 the outermost broken line indicates the display
screen portion and forms no part of the claimed design and
all other broken lines shown in FIGS. 1-2 represent portions
of the augmented reality graphical user interface and the
work area that form no part of the claimed design. In FIGS.
1-2 the three dot ellipses form no part of the claimed design.
